DESIGN FOR A COMBINED COMB AND NAIL
FILE CONTAINER OR THE LIKE

James Slater McHugh, Garden City, N. Y.

Application May 27, 1947, Serial No. 139,311

Term of patent 3½ years

(Cl. D86—8)

To all whom it may concern:

Be it known that I, James Slater McHugh, a citizen of the United States of America, residing at Garden City, in the county of Nassau and State of New York, have invented a new, original, and ornamental Design for a Combined Comb and Nail File Container or the like, of which the following is a specification, reference being had to the accompanying drawing, forming a part thereof, wherein:

Fig. 1 is a side elevational view of a comb showing my new design; and

Fig. 2 is an end elevational view of said comb.

I claim:

The ornamental design for a combined comb and nail file container or the like, substantially as shown.

JAMES SLATER McHUGH.
